UNITED STATES PATENT OFFICE.

HENRY WELLEN, OF NEW YORK, N. Y.

DESIGN FOR A TRAY FOR CUPS OR SIMILAR ARTICLES.

Application filed June 6, 1925. Serial No. 13,689. Term of patent 7 years.

To all whom it may concern:

Be it known that I, HENRY WELLEN, a citizen of the United States, residing at New York, county and State of New York, have invented a new, original, and ornamental Design for a Tray for Cups or Similar Articles, of which the following is a specification, reference being had to the accompanying drawing, forming a part thereof, which drawing is a plan view thereof.

I claim:

The ornamental design for a tray for cups or similar articles substantially as shown.

In testimony whereof I have hereunto set my hand on this 4th day of June A. D., 1925.

HENRY WELLEN.
